GEORGE E. CLEAVER, OF READING, PENNSYLVANIA, ASSIGNOR TO PENN HARDWARE COMPANY, A CORPORATION OF PENNSYLVANIA.

LOCK.

1,272,915.

Specification of Letters Patent. Patented July 16, 1918.

Application filed March 24, 1913. Serial No. 756,366.

To all whom it may concern:

Be it known that I, GEORGE E. CLEAVER, citizen of the United States, and resident of Reading, county of Berks, and State of Pennsylvania, have invented an Improvement in Locks, of which the following is a specification.

My invention has particular reference to that class of locks in which a single key is employed to operate both the latch bolt and the dead bolt; and consists of many features of construction and combinations of parts adapted for giving to the lock capacity for more effective operation, all of which are fully set out hereinafter and more particularly defined in the claims.

My improvements will be described with reference to the accompanying drawings, which illustrate my invention in its preferred form, as a reversible mortise lock, of cylinder type and antifriction form.

Referring to the drawings: Figure 1 is a front end view of my improved lock applied to a door and showing the handles, key and turn knob; Fig. 2 is a side elevation of the lock proper with sideplate and key cylinder removed and the front plate in section; Fig. 3 is a transverse section of my improved lock on line $x-x$ of Fig. 2; Fig. 4 is a transverse section of the same on line $y-y$ of Fig. 2; Fig. 5 is a transverse section of the same on line $z-z$ of Fig. 2; Fig. 6 is a plan view of the turn knob cylinder removed and with the cap plate removed to show the interior construction; Fig. 7 is a cross section of the same on line $s-s$ of Fig. 6; Fig. 8 is a perspective view of the dead bolt and cylinder engaging lever; and Fig. 9 is a cross section of a portion of the case and an elevation of the cylinder engaging lever.

2 is the box portion of the case and is secured to the front plate 3, through which the bolts are shot. The open side of the case 2 is closed by a removable side plate 4 (Figs. 3, 4 and 5). 5 is the dead bolt and is provided at its rear end with the slot 7 and the talons 9 and 10 with a tumbler space between them, and a notch 19 in front of the forward talon. The slotted portion 7 fits over a guide lug 8 extending from the case 2 and acts to guide the rear end of the dead bolt. 11 is a tumbler, hinged at 12

to the dead bolt and having a part extending upward between the talons 9 and 10. A 55 spring 13 may be employed to normally hold the tumbler 11 in the up or locking position. This tumbler may be made in any suitable manner. As shown, its notches 11^a and 11^b engage the part 8^a of the lug 8, to hold the 60 bolt in its locking and unlocking positions.

Arranged under the dead bolt and pivoted to the case 2 at 15, is the roll-back engaging lever 14, the construction of which is best shown in Fig. 8, constituting a lever having 65 the arm 16, the notch 17 and the finger 17^a. As shown in Fig. 8, the side of the dead bolt 5 is provided with a lug 18, which at times operates to hold the lever 14 against oscillation (Fig. 2) and at other times, when in 70 the notch 17 (Fig. 8), will cause the bolt to be shifted by action of the lever 14 when actuated by the cylinder mechanism.

46 is the key cylinder and may be of any suitable construction; it is screwed into the 75 side plate 4 and provided at its inner end with the operating cam 47 which is arranged to coact with the talons 9 and 10 of the dead bolt, the tumbler 11, and the roll-back engaging lever 14 above referred to. Arranged in the opposite part of the case, is the unit turn knob cylinder 48, also screwed into the case to secure adjustable attachment, and having the cam 49 for operating upon the parts 9, 10, 11 and 14, this operation taking place from the turn knob 56 (Fig. 1).

The end 16 of the roll-back engaging lever 14 coacts with the latch lever 20, pivoted to the case at 21, to rock it and thereby withdraw the latch bolt 6 against the action of 90 its spring 33. The end of the latch lever 20 engages with the transverse end 22 of the latch bolt (Figs. 2 and 5), said construction permitting the latch bolt to be reversed, as hereinafter described. With the parts 95 above described and as shown in Fig. 2, it will be seen that the lever 14 is held in gear by the dead bolt, which passes over it in such manner that the lever is in range of the cylinder cam 47 until sufficient protraction of the dead bolt carries it away as intended; or vice versa. This is necessary for those cases where the dead bolt might be unintentionally or unnecessarily partly protracted or retracted by the turn knob mechanism, so that the cylinder cam may be en-

abled to act to protract the bolt totally by getting against the rear auxiliary shoulder 9^a of the rear talon, or retract the bolt by contact with the upturned arm 14^a of the said lever 14 which is held by the bolt, (while in motion) in position for contact, as long as the said rear shoulder 9^a is not sufficiently forward to be used. It will be understood that in the normal or usual way of 10 turning the cylinder cam 47 or turn hub cam 49 against the end of the lever 14, both it and the latch lever 20 will be tumbled and the latch 6 retracted. The finger 17^a of the lever 14 is prevented from getting out of 15 position while the dead bolt 5 is retracted, because of the lug 18 of the dead bolt. It will be seen that the bolt may be moved forward a distance, a little greater than the length of this lug 18, before the lever 14 can 20 possibly rotate to get its upper end out of range with the cylinder cam. In this position, the lug 18 enters the notch 17 as shown in Fig. 8 and, striking against the lever 14, oscillates it out of reach of the cylinder cam. 25 In the reverse movement, should the bolt 5 be only partly retracted, this action will cause the lug 18 to press against the finger 17^a and oscillate the lever 14 to the position substantially as shown in Fig. 2, preferably 30 before the retraction is half way completed, and in which position the cylinder cam may reach and operate the lever 14 to retract the latch bolt 6; and at the same time, by the action of this lever upon the lug, force the 35 dead bolt fully back to its retracted position as shown. The lever 14 then, when released returns to the position shown in Fig. 2 under the action of the latch bolt. In this way, not only may the dead bolt be operated in 40 the usual way, but provision is made to properly project and retract it from intermediate and unintentional positions into which it may accidentally be brought.

The turn knob cylinder 48 is shallow and 45 recessed as at 57 and covered with a plate or cap 58 which may be secured in place by screws or rivets or in any suitable manner. The interior of the cylinder is provided at the upper end with a horse-shoe shaped recess 61^a, provided for receiving a looped end 61 of a wire spring 60 and holding it in position. This wire spring 60 has downwardly extending free parallel ends and bends 60^a to lengthen the wire of the spring and give 55 more elasticity, thereby permitting a stronger wire to be employed than if the spring were shorter. The wire composing this spring all lies in the same plane and consequently takes very little space, thereby permitting a very 60 shallow cylinder 48 to be employed. The free ends of the spring 60 press upon the flattened sides of the turn hub and socket 59 which is journaled in the cylinder and secured on its outer end with the cam or operating bar 49, previously referred to. The

turn knob 56 (Fig. 1) may have the usual square shank to fit the square hole in the hub and socket 59. When the turn knob is rotated, it rotates the socket 59 and cam 49 to operate the latch bolt when the dead bolt 70 is retracted, as shown in Fig. 2.

The particular construction of cylinder engaging lever 14 of the latch operating mechanism, having, as it has, a movement approximately in a curvilinear direction with 75 a throw of the dead bolt, and being so compact as to be practically contained within said bolt and not interfering with the movements of the turn hub cam, or any other lever, slide or projection, which might be a 80 hindrance to the movement of the lever in question without cutting away some of the lever, may be considered as a material portion of my invention. The special object of this lever 14, other than its action upon the 85 latch lever, is to clear everything, with its upturned end 14^a sweeping the full inside of the case, so as to obtain the benefit of adjustment of the cylinders to the full value of the width inside of the case. As far as I 90 am aware, such construction of lever has not heretofore been employed where a turn hub and cam are operated from a point within the cylinder hole of the case.

As both the key cylinder 46 and turn hub 95 cylinder 48 are required to be held against rotating when once adjusted, I provide set screws 50 for this purpose, said screws being so secured to the case that they cannot become accidentally disengaged and lost. In 100 the construction shown, these set screws 50 are screwed through threaded bosses 51 on the case parts 2 and 4 and provided with pointed ends to engage V-shaped notches in the cylinders, said screws being further provided with collars 52 at a distance from their slotted ends, which are held between shoulders 53 on the case parts 2 and 4 and the front plate 3. The ends of the screws 50 extend into holes 54 in the end plate 3 so as 105 to enable them to be rotated by a screw driver. There is sufficient space between the shoulders 54 and the front plate in which the collars 52 may move to enable the set screws to be fully withdrawn from the cylinder 3 before contacting with the front plate. In this way the threaded end and heads of the set screws are prevented from getting out of their respective co-operating holes, thereby preventing the losing of the screws 110 inside the lock or separating therefrom.

Referring now to the latch bolt 6 and its associated parts: The latch bolt body 29 is made with an open slot and is fitted with a rod or guide tube 30 of rolled or drawn metal thereby providing a smooth guide at 115 low cost. This guide tube or rod 30 is held in place by having one end fitted to a projection 30^b, and the other end received in a recess and held therein by having the lug 30^a 120 130

bent over it (Figs. 2 and 5). This guide 30 is arranged in a slot of the lug 31 extending up from the side of the case 4, but of a size which clears the sides of the body 29 so as to 5 avoid all unnecessary friction. The rear end of the bolt 6 has a tail 22 forming lateral projections upon each side of the body and acting with the sides of the case as a laterally guiding means. The bolt is guided vertically by the part 23^a of the knob hub lever 23 and the fixed lug 62. A coil spring 33 surrounds the guide tube or rod 30 and has one end pressing against a washer 32 surrounding the said guide, and resting against 10 the slotted lug 31, said spring acting to normally protract the latch bolt and maintain the latch lever 20 in operative relation with the arm 16 of the roll-back engaging lever 14. The fixed lug 62 acts not only as a guide 15 for the tail end of the latch bolt, but also has a limit stop in its protraction, because it acts as a stop for the end of the latch lever 20 and the latter directly acts as a stop for the part 22 of the latch bolt. This holding of 20 the end of the latch lever 20 between the parts 22 and 62 prevents this lever from getting out of engagement with the lever 14 when the dead bolt is protracted, and also prevents possibility of having these levers 25 become dead locked and thereby dogging the dead bolt.

As my improved latch bolt contains the coil spring 33 as a unit with it, no handling of the latch bolt or separation of it from the 30 remaining portions of the lock, can disengage the proper relation of this spring with the latch bolt. Moreover, the guide tube or rod 30 acting as a support and guide for the coil spring, allows a suitable spring to be 35 employed which will exactly meet the requirements of the bolt without necessitating that the spring be abnormally stiff. An advantage of my improved retained box latch bolt spring and latch construction shown is, 40 that the bolt has its own spring and is cast to length without particular alterations, as against a bar bolt heretofore employed with a riveted tail piece which must be fitted, and if not done well, will loosen in time. Other 45 bolt shanks which have been cast in one piece have always had coil springs as a separate piece, said springs floating, as it were, and ready to jump out any time the lock cap was removed, and which also on reversing 50 the bolt requires it to be reversed separately and the spring applied afterward. It has heretofore been found, that if the separate springs were not set in properly, or if the lock were not fitted in a good workmanship manner, such spring would scratch and retard action. In my improved bolt, however, the spring is held in place at all times by the smooth guide rod or tube 30, and there is no possibility for the spring becoming disengaged or taking an undesirable shape.

The head of the latch bolt 6 is shown as provided with the usual inclined surfaces 34 and with an intermediate slot 35 in which is arranged the antifriction center buffer 36. This antifriction center buffer 36 is provided 70 at its axial end 37 with a semi-cylindrical portion which fits into a recess 37^a formed between the end plate 3 and case plate 4. The case plate 4 is provided with a recess 4^b having guide ribs 4^a extending inward from 75 the recess 37^a and over which ribs the bolt head may slide with relatively small, if any, friction, the buffer end 37 rotating in the recess 37^a aforesaid. The opposite end of the center buffer 36 is provided with an extension 37^c which, acting against the bolt head, limits its outward movement, but said buffer is free to swing about its pivot end 37 in an inward direction and acts as a lever 80 in coöoperating with the part 34^a of the bolt 85 head to start the retraction of the latch bolt upon closing the door. This extension 37^c of the buffer 36 acts at all times to prevent disengagement of the buffer from the bolt head. I have shown the latch bolt as reversible and 90 this is made possible by providing between the end plate 3 and the bolt case 2 a similar recess 37^b to that shown on the opposite side at 37^a, and in further providing a case part 2 with the similar recess 2^b having guide ribs 95 2^a. It will be understood by reference to Fig. 5 that if the latch bolt 6 is reversed, the semi-cylindrical part 37 would fit into the recess 37^b, and the projecting end or extension 37^c of the buffer would then be received in the recess 37^a, just as it now is received in the recess 37^b. It will be seen 100 that both the head and tail of the bolt are each disposed substantially equally on each side of the guide 30, so that the bolt, as a 105 whole, may be reversed in the case and properly coöperate with said case and with the remaining operative parts of the lock structure. In my improved construction of anti-friction bolt, the latch bolt is provided with 110 a center buffer instead of a side buffer as heretofore commonly employed, and as shown, the bolt head is closed on the back of the part 34^a providing a broad back portion in connection with the center buffer, almost 115 hiding the buffer and strengthening the bolt and providing a central support for the guide tube 30.

My improved casing allows, not only of the employment of the antifriction buffer 120 with its reversible feature as above described and providing grooved portions 4^b and 2^b through which the antifriction central buffer may reciprocate when the bolt is retracted, but said recessed portions are provided with ribs or tracks 2^a and 4^a, and these may guide the solid portion of the bolt head and prevent it from falling laterally inside of the case when the bolt is retracted, should the antifriction buffer permit lateral 125 130

movement of the bolt head, said solid portions of the bolt being properly formed so that they would be guided by the ribs or tracks to bridge the gaps or recesses 37^a and 37^b when fully retracting the bolt, as will be understood by reference to Fig. 5. It will be understood that this same case may be used with a solid bolt head in which the buffer 36 is not employed, where such anti-friction device is not required. This would be equivalent to leaving the antifriction buffer 36 off of the latch bolt, whether because it was worn, injured or otherwise.

The knob hub lever 23 is pivoted to the case and normally held out of action upon the latch bolt tail by a spring 27 and with its free end resting under the tail 22 of the said latch bolt, for retracting it by operation of the door knob 28. This lever 23 has a portion 23^a which normally acts as a stationary lug for one part of the tail portion of the latch bolt, while a real fixed lug 62 on the case acts to guide the latch bolt at the other side of the tail portion when the latch bolt is withdrawn by other means than the door knob; said lever 23 acting as a moving guide for the latch bolt tail in conjunction with the above mentioned fixed guide lug 62 while the door knob with the hub is acting to withdraw or retract the latch bolt. The particular advantage of this is, that it produces a perfectly straight or rectilinear retraction of the latch bolt from one end to the other.

The knob hub lever 23 is operated by the split knob hub parts 24 and 24^a, either of which may be dead locked. The hub parts are journaled in the case and upon each other and have square holes 25 for the knob spindles or spindle by which they are rotated. These hub parts are respectively provided with notches 26 and 26^a either of which are adapted to receive the dead locking plunger 38 which is operated by the stops of the stop mechanism. This mechanism consists of two stops 43 and 44 made alike and working through apertures in the front plate 3 of the case. The inner ends of these stops have pins 40 and 45 which respectively fit in holes formed on opposite ends of the stop beam lever 41, pivoted at 42 to the case 2. The stop plunger 38 is guided in the case at 39 close to the hub part which it engages, and the other end is provided with a hole fitting upon the pin 40 of the stop 43. In this way the knob hub part may be dead locked or dogged by a construction which is simple, cheap and durable and so formed as to enable its parts to be interchangeable. The stop beam lever connects the stops to simultaneously reverse their movements and position their inner ends, and the operation of the plunger to lock the hub is a direct action from the stop 43 with which it is jointed. The end of the stop

beam lever 41 is made angular as at 41^a against which the spring 41^b acts to frictionally hold it in its two extreme positions of adjustment.

By the construction of stop mechanism here described, the plunger may be readily reversed to dead lock either of the halves of the split hub 24, 24^a, which does away with the heretofore more or less unsatisfactory way of fitting and reversing such a hub, and allowing more quick and positive action in reversing. The jointing of the long or locking stop, formed of the parts 43 and 38, enables the plunger part thereof 38 to be made of inflexible and cheap cast iron or other cheap metal, while the protruding stop part 43, having the head, can be of the usual brass or bronze; this construction also securing the positive action of the plunger, about as well as if made in one integral part with the stop.

In addition to the foregoing constructions my improved lock embodies an important novel feature, comprising automatic stop setting and stop locking means in the form of a lever 46, one end of which is arranged to be acted upon by the shoulder 5^a and lug 5^b of the dead bolt 5 and the other end caused to actuate the stop mechanism, in such manner that the protraction of the dead bolt always prevents the outer knob from being turned; this being accomplished by the dogging of the stop mechanism through the function of the lever 46, whereby the stop heads cannot be successfully tampered with. The lower end of this lever 46 engages the shoulder 38^a of the locking plunger 38, and when the dead bolt is protracted, the locking plunger is automatically moved into dogging or locking position to lock the knob hub part 24^a. When the dead bolt is retracted, there is no effect upon the stop mechanism because of the loose play for the end of the lever 46 between the shoulder 5^a and lug 5^b, so that the knob hub would never be undogged by the dead bolt. Therefore, the protraction of the dead bolt always automatically locks or dogs the outer knob (in case this knob has not been previously set by hand), thus always insuring that when the dead bolt is in locking position, the door also has the protection of the latch bolt as well, as far as knob operation is concerned. The retraction of the dead bolt does not upset the stops, therefore the stops are manually operated when it is desired that the outer knob be free to operate the latch bolt. It will be understood that, in the better class of door locks, the outer and inner door knobs are independent so that the inner knob may always be operated to withdraw the latch bolt, even when outer knob is dogged or held against movement, and this is intended to be so in the most preferred form of my invention; but it is evident that

it is not essential to have the knobs independent in action and hence it is to be understood that, if desired, the two knob hub parts may be cast integral and a solid spindle 5 employed, as is common in the cheaper locks.

I have, in the preferred construction, shown the roll-back engaging lever 14 in a form which will positively assist in fully retracting the dead bolt, should it be only 10 partly retracted from any cause, as well as for operating the latch bolt.

I have shown my improved lock in the specific form which I have found most satisfactory in practice, but I do not restrict 15 myself to the details shown as they may be modified in various ways without departing from the spirit of the invention, as defined in the claims.

Having now described my invention, what 20 I claim as new and desire to secure by Letters Patent is:—

1. In a lock, the combination of a dead bolt and its operating means, a latch bolt, hand operated means for operating the 25 latch bolt, stop mechanism for locking the hand operated means against movement and arranged to be moved manually for unlocking said means, and separate pivoted connecting means operated by the dead bolt and 30 its operating means when moved in one direction for automatically operating the stop mechanism in the other direction to lock the hand operated means and thereby the latch bolt whenever the dead bolt is protracted.

35 2. In a lock, the combination of the case, a bolt, a turn knob cylinder having a shallow chamber provided with a socket, an operating cam for operating the bolt journaled in the cylinder and having a double cam portion arranged in the shallow chamber thereof, and a retaining spring provided with a suitable bend to fit within said socket and having two free arms pressing upon the double cam portion for holding the operating 40 cam out of operating position, said spring formed of a bent wire having all of its portions arranged in one plane.

45 3. In a lock, the combination of the case, a bolt, a turn knob cylinder having a shallow chamber provided with a socket, an operating cam for operating the bolt journaled in the cylinder and having a double cam portion arranged in the shallow chamber thereof, and a retaining spring having two free 50 arms pressing upon the double cam portion for holding the operating cam out of operating position and also having a middle bend to fit the socket in the chamber and reverse bends between the free ends and middle bend to give great elasticity, said spring formed of a bent wire having all of its portions arranged in one plane.

60 4. In a lock, the case, combined with a dead bolt having a laterally extending lug, a cylinder and its operating cam, a lever

pivoted upon the case and held in position back of the dead bolt said lever having portions to be actuated by the lug of the dead bolt to oscillate the lever into or out of operative position to be acted upon by the 70 cylinder cam which operates the dead bolt and means forming a connection between said lever and said dead bolt to prevent independent movement of said lever or said dead bolt in partially retracted position of 75 the latter, whereby the dead bolt may be fully retracted when previously left in a partly retracted position.

5. In a lock, the case, combined with a dead bolt having a laterally extending lug, 80 a cylinder and its operating cam, a turn knob and its operating cam, a turn knob lever pivoted upon the case and held in position back of the dead bolt said lever having portions to be actuated by the lug of the 85 dead bolt to oscillate the lever into or out of operative position to be acted upon by the turn knob or cylinder cams which operate the dead bolt, and means forming a connection between said lever and said dead bolt to prevent independent movement of said lever or said dead bolt in partially retracted position of the latter, whereby the dead bolt may be fully retracted when previously left in a partly retracted position, a 90 latch bolt, and means to operate the latch bolt actuated by the turn knob lever.

6. In a lock, the case, combined with a dead bolt having a laterally extending lug, 100 a cylinder, and its operating cam, a turn knob and its operating cam, a turn knob lever pivoted upon the case and held in position back of the dead bolt said lever having portions to be actuated by the lug of the dead bolt to oscillate the lever into or out of operative 105 position to be acted upon by the turn knob or cylinder cams which operate the dead bolt, and means forming a connection between said lever and said dead bolt to prevent independent movement of said lever or said dead bolt in partially retracted position of the latter, whereby the dead bolt may be fully retracted when previously left in a partly retracted position, a latch bolt, means to operate the latch bolt actuated by the turn 110 knob lever, a knob and knob operated means for actuating the latch bolt, manually operated stop mechanism for locking the knob operated means against operation, and means actuated by the dead bolt in protracted position to cause the latch bolt stop mechanism to be locked.

7. In a lock, the case, combined with a dead bolt having a laterally extending lug and a notched upper portion, a cylinder and its operating cam for the bolt, a lever pivoted upon the case and held in position back of the dead bolt said lever having portions to be actuated by the lug of the dead bolt to oscillate the lever into or out of operative 125 position to be acted upon by the turn knob or cylinder cams which operate the dead bolt, and means forming a connection between said lever and said dead bolt to prevent independent movement of said lever or said dead bolt in partially retracted position of the latter, whereby the dead bolt may be fully retracted when previously left in a partly retracted position, a latch bolt, means to operate the latch bolt actuated by the turn 130 knob lever, a knob and knob operated means for actuating the latch bolt, manually operated stop mechanism for locking the knob operated means against operation, and means actuated by the dead bolt in protracted position to cause the latch bolt stop mechanism to be locked.

position to be acted upon by the cylinder cam which operates the dead bolt said portions comprising a notch into which the lug passes and presenting opposite faces against 5 which the lug acts to oscillate the lever in both directions and also having a projection over which the lug passes to hold the lever in operative position when the bolt is partly or fully retracted, whereby the dead bolt 10 may be fully retracted when previously left in a partly retracted position.

8. In a lock, the combination of a case, a dead bolt having operating talons, an oscillating cam for engaging the talons for 15 operating it, a lever pivoted to the case adjacent to the dead bolt and having a flange extending fully across the dead bolt and interior of the case in line with the travel of the oscillating cam, said lever being operated 20 by the dead bolt to be moved out of reach of the cam when the dead bolt is almost fully protracted and means to prevent independent movement of said lever with respect to said dead bolt in partially protracted or retracted position of said dead bolt.

9. In a lock, the combination of a case, a dead bolt having operating talons, an oscillating cam for engaging the talons for operating it, a lever pivoted to the case adjacent to the dead bolt and having a flange extending fully across the interior of the case and dead bolt in line with the travel of the oscillating cam, said lever being operated by the 35 dead bolt to be moved out of reach of the cam when the dead bolt is almost fully protracted and into reach of the cam when the dead bolt is partly or fully retracted and means to prevent independent movement of 40 said lever with respect to said dead bolt in partially protracted or retracted position of said dead bolt.

10. In a lock, the combination of a case, a dead bolt having operating talons, an oscillating double cam for engaging the talons for operating it, a lever pivoted to the case adjacent to the dead bolt and having a flange extending across the case in line with the travel of said double oscillating cam, said 50 lever operated by the dead bolt to be moved out of reach of one part of said cam when the dead bolt is fully protracted and into reach of the other part of said cam when the dead bolt is partly or fully retracted, means to prevent independent movement of said lever with respect to said dead bolt in partially protracted or retracted position of said dead bolt and a latch bolt and connecting means arranged to be operated by the double cam 55 when the dead bolt is retracted.

11. In a lock the combination of the case, a dead bolt, a lever pivoted to the case and having a mechanical connection with the dead bolt to prevent independent movement 60 of said lever with respect to said dead bolt

whereby the dead bolt may operate the lever and vice versa, and a manually operable cam for oscillating the lever and through it fully retracting the dead bolt when in partly retracted position.

12. In a lock, the combination of a case, a dead bolt slidably mounted in said case, a lever pivoted to the case and held in position by said dead bolt, means carried by said dead bolt for shifting said lever in either 75 direction according to the direction of movement of said dead bolt to retracted or protracted positions, cam means for operating the dead bolt and lever, a latch bolt and connecting means for retracting the latch bolt 80 by the lever when the dead bolt is retracted.

13. In a lock the combination of a casing, a dead bolt slidably mounted in said case, a lever pivoted to the case and held on its pivot by said dead bolt, means for operating 85 said lever when the dead bolt is partly retracted, and means forming a positive connection between said dead bolt and said lever whereby said dead bolt oscillates the lever to throw it out of operative position 90 with respect to the lever operating means when the bolt is fully protracted, and to move the lever into operative position when the bolt is partly or fully retracted.

14. In a lock, the combination with a dead bolt, of night latch mechanism, and means operable by the protraction of said bolt for dogging said night latch mechanism, said means including a pivoted lever having one end movable in contact with the dead bolt 100 and the other end in operative association with the night latch mechanism to move it when said lever is oscillated by the dead bolt.

15. In a lock, the combination with a dead bolt, of latch mechanism, dogging means for said mechanism, pivoted means having its opposite ends moving reversely and in which one end is in connection with the dead bolt and the other end with the dogging means, and manually operable means for jointly protracting said dead bolt and thereby the pivoted means for moving said dogging means into dogging position.

16. In a lock, the combination of a dead bolt, a latch bolt, manually operable retracting means for the latch and dead bolts, night latch mechanism associated with said latch operating retracting means, a movable part extending across the latch bolt having one end movably connected with the dead bolt and the other end with the night latch mechanism, and a separate mechanism operable from the outside of the door to retract said latch bolt or actuate said night latch mechanism as desired.

17. In a lock, the combination of a latch bolt, retracting means therefor, a night latch mechanism associated with said retracting means but arranged below the latch bolt,

with a dead bolt arranged above the latch bolt, and means comprising a shiftable member extending from the night latch mechanism across the latch bolt and in operative connection with the dead bolt for setting the night latch mechanism in dogging position automatically upon the protracting of the dead bolt.

18. In a lock, the combination with a latch bolt, of mechanism for actuating said latch bolt, independently operable stop mechanism for dead-locking said latch actuating mechanism, a dead bolt, and independent means for actuating said dead-locking stop mechanism adapted to be positively operated in one direction by the protraction of the dead bolt, said means having a lost motion connection with the dead bolt to permit resetting of the stop mechanism for releasing the latch operating mechanism when the dead bolt is retracted.

19. In a lock, the combination with a case, of a night latch mechanism at the lower part of the case, a dead bolt at the upper part of the case, a latch bolt intermediate of the dead bolt and the night latch mechanism, and means independent of both the dead bolt and the night latch mechanism extending above and below the latch bolt and operable by the protraction of the dead bolt for setting said night latch mechanism in dogging position, said bolt being retractable independently of said independent means and night latch mechanism.

20. In a lock, a case, a latch bolt therein, manually retracting means for said latch bolt, including a notched hub, a stop member in the case movable in and out of the notch of said hub, and separate means for actuating said stop member from the respective sides of the door, comprising a swinging lever having one end in movable connection with the stop member, a reciprocating member having a lost motion connection with the lever, a key mechanism at one side of the door to actuate the reciprocating member, and manually operable

means at the other side of the door to independently operate the reciprocating member.

21. In a lock, a latch bolt, combined with 50 retracting means therefor, night latch stop mechanism associated with said retracting means, a lever to operate said stop mechanism in one direction to lock the retracting means for the latch bolt and permit it to be 55 manually operated in the other direction to release said retracting means, and separately operable means at opposite sides of the door for actuating said lever to operate said night latch stop mechanism. 60

22. In a lock, a dead bolt, combined with a latch bolt, manually retracting means for the latch bolt, night latch stop mechanism associated with said means for dogging the same, means independent of the dead bolt 65 and stop mechanism for actuating the latter, and mechanism operable by a key from the outside of the door for retracting the latch bolt as the key is turned in one direction, and operating the dead bolt and the independent means for shifting the night latch stop mechanism into locking position as the key is turned in the opposite direction. 70

23. In a lock, the combination of a latch bolt, means controlled by outside and inside 75 knobs for independently retracting said latch bolt, stop mechanism arranged to be operated to dog the outside knob controlled means against latch retracting movement, a dead bolt, means operable from the side of 80 the lock which comes adjacent to the inside of the door for projecting said dead bolt, a vertically arranged lever pivoted so that its upper and lower ends move in opposite directions and for coincidentally operating 85 said stop mechanism to dog the outer knob controlled means, and means for operating the lever in one direction by the dead bolt.

In testimony of which invention, I hereunto set my hand.

GEORGE E. CLEAVER.
